(57) CLAIM

The ornamental design for a laundry sorter, as shown and described.

DESCRIPTION

FIG. 1 is a perspective front view of a laundry sorter;
 FIG. 2 is a front elevation view thereof; the rear elevation view being a mirror image thereof;
 FIG. 3 is a left side elevation view thereof; the right side view being a mirror image thereof;
 FIG. 4 is a top elevation view thereof; and,
 FIG. 5 is a bottom elevation view thereof.
 The broken lines shown in the drawings that illustrate additional bags form no part of the claimed design.
